Inventor:
George W. Du Nah
By Arthur A. Macd
Attorney.

UNITED STATES PATENT OFFICE.

GEORGE W. DU NAH, OF PASADENA, CALIFORNIA.

GLOVE-DRYING MACHINE.

Application filed August 19, 1920. Serial No. 404,632.

To all whom it may concern:

Be it known that I, GEORGE W. DU NAH, a citizen of the United States of America, and a resident of Pasadena, in the county of 5 Los Angeles, State of California, have invented new and useful Improvements in Glove-Drying Machines, of which the following is a specification.

My invention relates to and has for a 10 main object the provision of a mechanical dryer for kid gloves and the like, whereby the gloves after having been first cleaned may be deposited in the machine and tumbled or agitated in such a manner and to 15 such an extent as to thoroughly dry and keep the gloves soft after the application of the cleaning compound or liquid.

It is well known that when kid gloves and the like are cleaned in liquid such as gasoline if the gloves are allowed to dry they become stiff and must be worked by hand in order to preserve or restore the natural softness of the kid, and it is an object of 20 this invention to accomplish this same result 25 by the use of machinery so that a substantial economy may be effected by its use.

A further object is to provide in a machine of the character mentioned a suitable cabinet having a rotatable tumbler 30 therein, means for inducing currents of air at the exterior of the cabinet into contact with and to the interior of the tumbler, and means for applying heat to the air currents for facilitating the drying operation. 35 Other objects may appear as the description progresses.

I accomplish the above objects by means 40 of the mechanism shown in the accompanying drawings of my invention, in which: Fig. 1 is a side elevation of my machine, partly in section; Fig. 2 is a rear elevation of the same; Fig. 3 is an enlarged section of the tumbler element; Fig. 4 is a sectional elevation, and Fig. 5 is a sectional plan.

Briefly described, my invention consists 45 of a suitable cabinet C having a rotatable tumbler T therein and operated by a suitable driving means D, an air inlet I having a fan f mounted in the end thereof, and a steam coil S mounted within the cabinet C above the tumbler T and below the mouth of the air inlet I.

Cabinet C has a top 1, bottom 2, sides 50 3, 3, and ends 4, 4 carried on legs 5, 5, etc. which are adapted to rest upon the floor and provides a rectangular enclosure for

receiving the currents of air for drying the gloves and for enclosing the tumbler T which is rotatably mounted on a transverse driving shaft 6 and held in bearings 7, 7, 60 in the ends 4, 4. One of the sides 3, 3 is provided just above the floor 2 with a hinged door C' which opens outwardly, as shown by broken lines in Fig. 2, and the front end 4 has a removable panel P which 65 forms the upper portion of the end and is adapted to be removed for the purpose of depositing the gloves in the tumbler T. Said door and panel may be suitably held in closed position by latches (not shown), 70 or otherwise.

A frame F composed preferably but not necessarily of pipe lengths and fittings is attached to the rear side 4 and floor 2 of the cabinet C and includes a central bearing member 7 in which a counter-shaft 8 is journaled at its outer end, the inner end of said counter-shaft being carried in a bearing 9 attached to the rear side 4 of the cabinet. Counter-shaft 8 is operated by 75 means of a driving belt B and a pulley 10 fixed to the counter-shaft, a companion loose pulley 11 being also provided on said counter-shaft for receiving the belt B when the machine is inoperative. The belt B may be shifted by the usual means applied to the belt adjacent to the pulley 10 or close to the driving pulley for said belt, not shown. 80

The inner portion of the counter-shaft 8 carries a gear G which meshes with and is 85 adapted to drive a relatively larger gear G' on the end of shaft 6, for operating the tumbler. Motion is transmitted to another upper counter shaft 12 near the top of the cabinet by means of a large sheave 13 on counter-shaft 8 and a crossed belt 14 operating thereover and over a smaller sheave 15 on the counter-shaft 12, the relative sizes of 90 said sheaves being such as to afford a substantial increase in speed of the shaft 12 as 95 compared with driving counter-shaft 6. Counter-shaft 12 is held in bearings 15 and 16 which are supported, respectively, on the rear end 4 of the cabinet and on a bracket 100 17 formed of pipe fittings, or otherwise. 105

Air inlet I is elbow-like in form and is of 110 sheet metal and has a removable end portion E thereon which encloses the fan f, as shown in Fig. 1. Fan f is carried on a horizontal shaft 18 held in bearings 19 and 20 which are supported, respectively, on frame members 21 and 22, formed of pipe fittings,

or otherwise. Fan shaft 18 is driven from countershaft 12 by means of sheaves 23 and 24 carried on said counter-shaft and fan-shaft, respectively, and a belt 25 operating over said sheaves. Thus the fan *f* is rotated at a maximum speed and is operatively connected with the driving counter-shaft 8.

The tumbler T is composed of a plurality of chordal flat members 26, 26, etc. attached together in the form of an octagon or other geometric figures, ends 27, 27, and longitudinal cleats, or baffles 28, 28, etc., attached to the members 26 at the intersections thereof, one of the members 26 being hinged, as shown by broken lines in Fig. 3, for affording access to the interior of the tumbler. A plurality of bores 29, 29, etc. are provided in the members 26 through which the air may be admitted to and discharged through the walls of the tumbler. Suitable bushings 30, 30 may be provided in the ends 27 of the tumbler for receiving the driving shaft 6, as shown.

The interior of the cabinet C is heated to a desired extent by means of a steam coil S having an inlet 31 and an outlet 32 with suitable valves, (not shown) therein and said coil is disposed horizontally in the top of the cabinet just above the tumbler T and below the mouth of the inlet I so that the air currents induced by the fan *f* may be heated prior to the circulation through the tumbler T.

It will be obvious that when the machine is in operation, the gloves to be dried having been first deposited in the tumbler T by the removal of the panel on the front of the cabinet and the opening of the hinged side of the tumbler, the rotation of the tumbler will maintain a movement, or agitation of the gloves within the tumbler while the drying is in progress, thus keeping them soft and pliable, and the induced air currents through the tumbler walls will serve to rapidly and effectively dry the gloves.

The above operation is effected at a minimum cost for labor and entirely by mechanical means, whereas heretofore it has been necessary to manipulate the gloves after cleaning so as to render them soft and pliable and restore them to their natural condition.

While I have shown and described only one practical embodiment of my invention,

it will be understood that I may modify and alter the form of the several contributing elements of my mechanism within the scope of the appended claims without departing from the spirit of my invention.

What I claim is:

1. A glove drying machine comprising a cabinet having a door at the lower part and a removable panel at the upper part, a tumbler located in the cabinet, means for rotating the tumbler, a forced draft air-inlet communicating with the upper part of the interior of the cabinet, and a heating coil located within the cabinet between the forced draft air-inlet and the tumbler.

2. A glove drying machine comprising a cabinet, a tumbler located in the cabinet, having a door at the lower part and a removable panel at the upper part, means for rotating the tumbler consisting of a driving shaft on which the tumbler is mounted, a counter-shaft, fixed and loose pulleys on the countershaft, gearing connecting the countershaft with the driving-shaft, a forced draft air-inlet communicating with the upper part of the interior of the cabinet and a heating coil located within the cabinet between the forced draft air-inlet and the tumbler.

3. A glove drying machine comprising a cabinet, a tumbler located in the cabinet, having a door at the lower part and a removable panel at the upper part, means for rotating the tumbler consisting of a driving shaft on which the tumbler is mounted, a lower countershaft, fixed and loose pulleys on the lower countershaft, gearing connecting the countershaft with the driving shaft, a forced draft air inlet communicating with the upper part of the interior of the cabinet, a fan located in the forced draft air inlet, a shaft on which the fan is carried, an upper countershaft, driving means connecting the lower countershaft with the upper countershaft, driving means connecting the upper countershaft with the fan-shaft, and a heating coil located within the cabinet between the forced draft air-inlet and the tumbler.

GEORGE W. DU NAH.
